DEVICE FOR FEEDING MACHINES FOR PACKING TUBULAR PRODUCTS

Filed Dec. 30, 1942

UNITED STATES PATENT OFFICE

2,376,651

DEVICE FOR FEEDING MACHINES FOR
PACKING TUBULAR PRODUCTSGerard Bardet, Paris, France; vested in the
Alien Property CustodianApplication December 30, 1942, Serial No. 470,616
In France July 16, 1941

3 Claims. (Cl. 198—20)

Certain machines, like those for packing cigarettes, macaroni, and the like, require that the products to be packed should be fed to them in orderly arranged definite quantities.

The systems using simple travelling bands and the like do not accomplish the desired results principally because the proper grouping and packet arrangement of the products cannot be effected without difficulty, especially when substantial outputs are to be attained.

It is an object of the present invention to provide a device which insures rapid and accurate feeding of successive groups of articles to a packing machine, said device including a distributing chain, carrying feeders in which the tubular products are poured in the desired quantity.

The tubular products to be packed are fed from a magazine upon a pair of spaced bands. The chain and associated feeders move between the bands at such a relative inclination that the feeders are filled one by one with the products disposed upon the bands. As the chain continues to travel, the filled feeders are moved toward a packing device.

A preferred embodiment of the subject matter of the invention will now be described in detail with reference to the accompanying drawing, in which:

Fig. 1 is a vertical longitudinal sectional view of the device.

Fig. 2 is a plan view.

Fig. 3 is a sectional view taken along the line III—III in Fig. 1.

The tubular products, for instance cigarettes, are housed in a magazine 2, the bottom of which is formed by two endless bands 3 and 4 which in turn are spaced apart. An outlet is provided between the upper surfaces of said bands and the front edge 5 of the magazine. A vertical wall 16 extends throughout the length of the device and constitutes one of the sides of the magazine 2, the other side of the magazine remaining open.

An endless chain or apron 6 is arranged beneath the bands 3 and 4, said apron 6 being carried by two pulleys 7 and 8, one of said pulleys being employed as a drive. Pulley 7 has a shaft 10 extending therefrom, and upon this shaft a second pulley 7' is secured, said pulley 7' having a belt 9 mounted thereon. The belt 9 is also mounted upon another pulley 11' fixed upon shaft 11, which shaft supports pulleys 19 and 20 upon which belts 3 and 4 are mounted.

Similar pulleys 19a and 20a also support the belts 3 and 4 at the other end of the machine. Suitable feeders 12 are placed side by side on said

chain or apron 6, each feeder comprising a base 14 having four identical sheet metal plates 13 extending therefrom in such a manner as to form three chambers 15.

8 The operation of the device is as follows:

When the apron 6 is set in motion, the bands 3 and 4 move in the direction of the arrow F and remove the products from the bottom of container 2. The removed products are then deposited in chambers 15 as the feeders move between the bands. Since belts 3, 4 are disposed at an angle with chain 6, the transfer of the products is effected substantially at the intersection.

15 The products 1 fill the chambers 15, and the feeders thus filled continue to advance until they come in proximity to a packing machine (not shown). A hand 16a then moves into engagement with the products in chambers 15 to 20 thereby transfer the products from the feeder to the packing machine. The hand 16a is indicated in dotted lines in Fig. 2.

A simple or compound scraper or similar device 17 serves to remove the surplus products 25 from the feeders 12. According to an arrangement illustrated in the drawing for packing cigarettes, a push-piece 18 is slidably mounted in each member 14 below the center chamber 15.

The lower or tail ends of pieces 18 successively 30 engage a cam or incline 18a as the top section of chain 6 moves from right to left. The incline 18a raises the center stack of cigarettes a distance equal to the diameter of one cigarette immediately after the three chambers of each feeder 35 are filled and before the center chamber reaches the scraper 17. After passing beneath the scraper, the push-piece falls back again before the feeder moves to a position opposite the hand 16a. In this manner, each of the outer chambers 40 of each feeder has seven cigarettes therein and the central chamber has six cigarettes, each outer chamber being slightly offset relative to the central chamber. Moreover, by the same process, other asymmetries can be obtained in the 45 filling of the chambers.

It is to be understood that the invention is not limited to this arrangement of the feeders and to the conveyor chain.

The chain 6 is illustrated as being inclined 50 relative to the horizontal at a substantial angle. This inclination compels the products which have been unable to find a place in the chambers 15 to redescend towards the mass of those which are constantly drawn along by the bands 3 and 4. 55 It is important to notice that, even with a chain

which is not inclined or only slightly so, the bands 3 and 4 accompany the products until the lowermost cigarette touches the bottom of its respective chamber. The cigarettes are thus arranged in the proper order with a minimum amount of displacement, thereby avoiding the deterioration of the products and the possibilities of their becoming wedged.

The chambers can be of various shapes and arrangements, according to the nature of the product to be packed. Of course, the number of chambers can be varied as well as the manner of pivoting the feeders on the chain or apron. The methods for driving the chain and the bands can obviously be varied.

Finally, the ratio between the movements of the respective belts 3, 4 and 6 can be regulated at will by any suitable means such as a speed varying device of known type to suit operating conditions. Such a device will, among other things, serve to accelerate or to slow down the flow of products towards the scrapers 17.

In the present instance, the pulleys 19 and 20 are somewhat larger than pulley 11'. Also, pulley 1' is larger than pulley 11'; consequently, the belts 3 and 4 will travel faster than belt 6, and as a result the cigarettes 1 will accumulate in sufficient depth in front of the scraper 17 to fill the chambers 15.

I claim:

1. A machine for packing tubular products comprising two parallel conveyor bands, means for delivering a supply of said products upon said bands, an endless apron obliquely arranged between said bands, said bands and apron being

5 mounted for movement substantially in the same general direction, a portion of said apron projecting above the bands, feeder units for receiving the product from said bands, each unit including an assembly of spaced sheet metal plates on a base, and the base of each unit being secured to the apron, a push-piece slidably mounted in each of said bases and projecting into one of the spaces between the plates into engaging position with said products, cam means for successively urging each push-piece into its associated space to elevate the products therein, and a scraper flush-top with said feeders for removing the products disposed above the top level of the filled units.

10 2. A machine for packing tubular products comprising a conveyor formed from a plurality of containers arranged side by side, each container having a plurality of open flush-top compartments, means for delivering a continuous supply of said products to fill said compartments, means for elevating the delivered products in a designated compartment of each container, and means for removing the products disposed above the tops of all of the compartments while the products in said designated compartment are in elevated position.

15 3. A machine for packing tubular products comprising a conveyor, means on said conveyor for supporting a plurality of parallel columns of said superposed tubular products, a stationary scraper for successively removing the products disposed above a given level from each of said columns, and means disposed in advance of said scraper for elevating some of said columns.

GERARD BARDET.
